UNITED STATES PATENT OFFICE.

AUGUST E. JOHNSON AND CARL NELSON, OF ELGIN, ILLINOIS.

OPERATING MECHANISM FOR WINDMILLS.

1,148,172.

Specification of Letters Patent. Patented July 27, 1915.

Application filed April 24, 1914. Serial No. 834,044.

To all whom it may concern:

Be it known that we, AUGUST E. JOHNSON and CARL NELSON, citizens of the United States, and residents of Elgin, in the county 5 of Kane and State of Illinois, have invented certain new and useful Improvements in Operating Mechanism for Windmills; and we do hereby declare that the following is a full, clear, and exact description thereof, 10 reference being had to the accompanying drawings, and to the characters of reference marked thereon, which form a part of this specification.

This invention relates to improvements in 15 operating mechanism for windmills for pumping water and like work and the invention consists in the matters hereinafter set forth and more particularly pointed out in the appended claims.

20 Among the objects of the invention is to provide an improved connection between the gear wheels, that may be operated through the usual windwheel, and the pump rod or other driven element so constructed 25 and arranged as to translate the rotary motion of the power shaft into rectilinear motion of the pump rod, so as to thereby transmit the power of the motor directly to the pump beneath and, therefore, more efficiently utilize the power, and to avoid side 30 thrusts on the bearings of the pump rod and consequent wear of the bearings.

A further object of the invention is to 35 provide an improved mounting for the gears and lever elements of the mill mechanism, the mounting having the form of a casing to inclose the mechanism and to contain oil in which the mechanism runs, and so arranged that free access may be had to the 40 various gears, lever elements and bearings upon the mere removal of a relatively light cap or cover and without dismantling the operative parts of the machinery.

Another object of the invention is to simplify and improve mechanism of this general character.

In the drawings:—Figure 1 is a partial side elevation and partial vertical section of a windmill embodying our invention. Fig. 50 2 is a plan view, with parts shown in section. Fig. 3 is a vertical section on the line 3—3 of Fig. 1. Fig. 4 is a fragmentary section of the bearing box for the power shaft and the pinion, showing means to deliver oil to the power shaft. Fig. 5 is a

fragmentary side elevation of the brake drum and brake band for the windwheel and the parts associated therewith. Figs. 6 and 7 are views, diagrammatic in their nature, illustrating different positions of the essential parts of the machine. Fig. 8 is a fragmentary view taken on the line 8—8 of Fig. 5.

As shown in the drawings, 10 designates the apex of the supporting tower provided at its upper end with a guide and bearing 65 11, downwardly through which extends a tubular stem 12, which is rotatively mounted and supported in any suitable manner (not shown) on the tower. The stem carries at its upper end the frame for the operative 70 parts of the mill, said frame assuming the form of an upwardly opening hollow casing 14 of a shape suitable to receive, inclose and support the various elements of the mechanism and to contain a lubricant in which the 75 mechanism runs.

16 designates the power shaft of the machine which is mounted to rotate in suitable bearings 17, 18 supported in the side walls 19 of the case-like frame 14 and carries at 80 its end, outside of the casing, the hub 20 of the wind wheel (not shown). The power shaft 16 carries within the casing two rigidly fixed, laterally spaced pinions 21, 21 which mesh with two large gear wheels 22, 85 22 that are rotatively mounted on studs 23, 23 which are attached to and extend inwardly from the side walls 19 of the casing 14. Arranged between said gear wheels 22, 22 is a pump rod 25, which extends 90 downwardly through a suitable upstanding tube 26 that rises from the bottom wall 27 of the casing through the hollow stem 12 for connection with a pump below. Said pump rod is attached at its upper end in any 95 suitable manner to a horizontal cross-head 28 which extends between and is rockingly mounted at its ends in the upper ends of a pair of pitmen 29, 30 arranged between the gear wheels 22 and one at each side of the 100 rod. Said pitmen are provided at their lower ends with laterally and oppositely extending socketed projections 31, 31 which engage over and have bearing on crank pins 32, 32 fixed in any suitable manner to the 105 gear wheel. Preferably, the said crank pins, which may be made of steel, are fixed to the gear wheels by being cast therein. Arranged between the said pitmen 29, 30 and extending at its upper end beyond said pit-

men is an oscillating block 35 which is preferably made of wood and faced at its sides by cheek plates 36, 36. The said oscillating block is cut away at one edge to provide 5 a recess 37 to receive the upper end of the pump rod and the cross-head 28 extends through apertures in the cheek plates 36, and into bearings of the pitmen beyond the same, and the parts may be held together by 10 a bolt 40 which extends axially through the cross-head and provided with a locking nut 41.

45 designates a standard which rises from the end wall 46 of the supporting casing.

15 47, 47 designate links which are pivotally connected by means of a bolt 48 to the upper end of said standard, and are pivotally connected at their other ends by a pivot bolt 49 to the upper end of the oscillating block 35.

20 50 designates a shorter standard which rises from the opposite end wall 51 of the casing, and 52, 52 designate links which are pivoted at their outer ends by a bolt 53 to said standard 50 and are pivoted at their 25 inner ends by a pivot bolt 44 to the lower end of the oscillating block 35. The said links 47 and 52 fit on the outside of the cheek plates 36 of the oscillating block and the bearings for the pivot bolts 49, 44 are therefore, partially supported by said cheek plates.

In designing the machine, the distance between the pivot bearings at the upper ends of the standards 45, 50 and the distance be-

35 tween the axis of the cross-head 28 and the pivots 49 and 44 of the links 47, 52, respectively, bear an approximately given relation to the length of the stroke of the pump rod. We have found that the best re-

40 sults are secured, with respect to rectilinear motion of the pump rod, when the distances between the axis of the cross-head and the pivot bolts 49, 44 is not less than one-half of the length of the stroke of the pump rod,

45 and with the distance between the planes of the pivots 48 and 53 not less than the length of the stroke of the pump rod. For example, when the stroke of the pump is six inches, the distance between the cross-head and the pivots 49, 44 should be in the neighborhood of three inches, and the distance between the plane of the pivots 48 and 53 should be substantially six inches.

50 A comparison of Figs. 1, 6 and 7 indicates the relative positions of the pitmen 29, 30, the oscillating block 35 and the upper and lower pairs of links, 47, 52 in a cycle of operation of the mill, and thereby indicates the manner in which is maintained rectilinear direction of motion of the pump rod. Thereby the relation of the pump rod to its upper bearing is preserved and side thrusts against said bearing, as well as 55 against a lower bearing against which the rod may act is avoided.

The length of the stroke of the pump rod may be increased relatively to the proportions just referred to without varying the rectilinear motion of the pump rod. To this end each of the gear wheels 22 may be provided with two or more crank pins 32, located at the same or different distances from the axis thereof. By locating the crank pins at different distances from the axis of the gear wheels variations in the pump rod 70 stroke is provided. Moreover, the provision of a plurality of pairs of crank pins located at the same distance from the axis of the gear wheels permits the pitmen to be adjusted or changed from one pair of crank pins 75 to another without varying the stroke of the pump. This is a material advantage inasmuch as the more severe wear occurs between the pitmen and said crank pins.

The oscillating block 35 is preferably 85 made of wood, and may be oil boiled wood, in order that it may carry the oil to the bearings associated therewith. Furthermore, in order to assist in carrying lubricating oil to the bearing for the cross-head, 90 we may place at one side of the rocking head and mounted on the adjacent end of the cross-head, a wood or other fiber strip 55, which during the reciprocating motion of the pitmen, is carried downwardly to 95 or below the upper side of the adjacent gear wheel 22 from which it receives oil and carries it to the cross-head bearing.

In order that the power shaft 16 may be kept suitably lubricated, we provide the construction best shown in Figs. 2 and 4. By reference to Fig. 4 it will be noted that the bearing 17 for one end of the power shaft is provided with an upwardly opening recess 58, the bottom wall of which tapers outwardly from the adjacent pinion 20 toward the side wall 19. The said bearing is provided at the lower part of its inclined bottom wall with an oil opening 59 that conducts oil to the bearing between the shaft 100 and the bearing box. The said shaft is longitudinally inclined in a direction the reverse of that of the bottom wall of the recess 58 so as to conduct oil that is carried thereto along the shaft throughout the principal 110 length of the bearing 17 back to the oil reservoir. The pinion 21 adjacent to the bearing box 17 is provided with an annular rim 59' which travels in peripheral contact with an annular surface 59² of its mating gear 120 wheel 22, whereby oil is carried to and delivered in the recess 58. The bearing 18 is supplied with oil from the casing 14 by the adjacent pinion 21 which receives oil from its mating gear wheel 22.

The bearing box 18 may be removably supported in a laterally extending hollow seat formed in the adjacent side wall 23 and is shown as provided with angularly spaced ribs to engage notches in the seat, whereby 130

said bearing box is held fixed, and may be, by removal and partial rotation thereof, adjusted to compensate for wear.

60 designates the vane frame which is mounted to swing laterally on a vertical pivot rod 61 that is seated in a vertical bearing 62 shown as cast integral with the casing. The said vane frame is adapted to be swung into a position parallel with the plane of the wind wheel to throw the mill out of the wind by means of a chain 65 attached at one end thereof to the vane and carried forwardly about a pulley 66 supported in a casing 67 that is attached to or made part of the casing 14; said chain being thence carried inwardly over a second guide pulley 68 and thence downwardly through the tube 26 and through the hollow stem 12 for connection, at its lower end, with a manually operating device. A guard 68', preferably made part of said tube, partially covers the chain and pulley and prevents escape of oil through the tube.

The vane is swung into the wind, when the chain 65 is released, by means of a weighted arm 70 carried by one arm of a bell crank lever 71 that is fixed to a rock shaft 73 mounted in a suitable bearing 74 at one end of the casing 14, the other end of the said bell crank lever being connected by a link 75 with the vane frame. A buffer rod 76, pivotally attached to the pulley casing 66 and extending through a guide opening in the vane frame, carries buffer springs 77, 35 78 to cushion the opening and closing movements of the vane.

The rock shaft 73 is provided on its end remote from the bell crank lever 71 with a short crank arm 80, shown best in Fig. 5. 40 81 designates a flexible brake band that encircles a brake drum 82 carried by the hub 20. The said brake band is attached at one end to a lug 84 on the casing. It is provided at its other end with a down-turned terminal 85 which is apertured to receive an adjusting bolt 86 that is pivoted to the lower end of the crank arm 80.

87 designates a clip, slotted to pass over the brake band, and the depending end of the clip is apertured to receive the adjusting bolt. As herein shown, the said bolt is screw-threaded to the clip and is locked thereto by a nut 88. Any other suitable means may be provided, however, to fix the bolt to said clip. The clip 87 is provided at its upper edge with an angular portion 90 which overlies the brake band, as shown in Fig. 4.

When the vane is thrown out of the wind the rock shaft 73 is operated, through the link 75 and bell crank lever 71, to tighten the brake band on the drum and thereby prevent the wheel turning. When the mill is thrown into the wind, the brake band is loosened. The angular extension or arm 90

which overlies the brake band serves to support the lower end of the brake band, and thereby serves as a support to prevent the band dropping to and riding on the brake drum when the mill is in normal operation. 70 Thereby undue wear and objectionable noise between the band and the drum, when the mill is in operation, is avoided.

The mechanism contained within and supported on the casing is inclosed above the casing by means of a cap 92 which is seated upon a flange 93 of the casing and secured thereto in any suitable manner. The said cap 92 constitutes merely a cover or protecting device and has no connection with the operative elements of the mechanism. Therefore, the removal of the cap exposes the mechanism so that repairs may be made without dismantling the parts of the mill not associated with the parts to be repaired. 85

We claim as our invention:—

1. In combination, a driven shaft, with means to drive it, a wheel operatively connected to and driven thereby and provided with a crank pin, a reciprocating element 90 extending across the face of said wheel and at one end thereof beyond the wheel and operative connections between said crank pin and the latter end of the reciprocating element including an oscillatory member 95 pivoted to the reciprocating element and to a fixed part to translate the rotary motion of said wheel into direct rectilinear motion of the reciprocating element.

2. In combination, a driven shaft, with means to drive it, a gear wheel rotatively geared to and driven by said shaft and provided with a crank pin, a reciprocating element, a cross head directly connected thereto and a pitman pivoted directly to said cross head and to said crank pin, with oscillatory means operatively associated therewith to translate the rotary motion of said gear wheel into direct rectilinear motion of the pump rod. 100 105

3. A windmill operating mechanism comprising a gear wheel, a driven shaft operatively connected to and driving said gear wheel, a reciprocating element, a pitman pivoted at one end to said element and at its other end to a crank pin carried by said gear wheel, an oscillating member pivoted between its ends to said element, and links pivoted at their inner ends to said oscillating member, one above and one below said reciprocating element pivot, and pivoted at their outer ends to fixed parts of the machine. 110 115 120

4. A windmill operating mechanism comprising a gear wheel, a driven shaft operatively connected to and driving said gear wheel, a reciprocating element, a pitman pivoted at one end to said element and at its other end to a crank pin carried by said gear wheel, an oscillating member pivoted between 125 130

- its ends to said element, and links pivoted at their inner ends to said oscillating member, one above and one below said reciprocating element pivot, and pivoted at their outer ends to fixed parts of the machine, the distance between the inner pivoted ends of said links and the reciprocating element pivot being not less than one half the stroke length of said element, and the distance between the planes of the outer ends of said links being not less than the stroke length of said element.
5. A windmill operating mechanism comprising a casing or frame, a motor driven shaft mounted therein, a disk driven by said shaft provided with a crank pin, a reciprocating element, a pitman connecting the said element to said crank pin, an oscillating member pivoted between its ends to said reciprocating element and links pivoted at their outer ends to fixed parts of said frame and pivoted to said oscillating member, one above and the other below the reciprocating element pivot.
10. A windmill operating mechanism comprising a frame, a motor driven shaft mounted therein, two pinions mounted on and spaced longitudinally of said shaft, two gear wheels meshing therewith and mounted in the frame, pitmen pivoted at their lower ends to crank pins on said gear wheels, a reciprocating element between said pitmen and pivotally connected at its upper end to said pitmen, and means associated with said pitmen and reciprocating element to translate the rotary movement of the gear wheels to direct rectilinear movement of the said reciprocating element.
15. A windmill operating mechanism comprising a frame, a motor driven shaft mounted therein, two pinions mounted on and spaced longitudinally of said shaft, two gear wheels meshing therewith and mounted in the frame, pitmen pivoted at their lower ends to crank pins on said gear wheels, a reciprocating element between said pitmen and pivotally connected at its upper end to the upper ends of said pitmen, and an oscillating member between said pitmen pivotally connected to the frame and to said reciprocating element.
20. A windmill operating mechanism comprising a frame, a motor driven shaft mounted therein, two pinions mounted on and spaced longitudinally of said shaft, two gear wheels meshing therewith and mounted in the frame, a reciprocating element between said gears provided with a cross-head, pitmen pivoted to crank pins on said gear wheel and to said cross-head, an oscillating member between said pitmen and pivotally connected between its ends to said cross head and pivotal connections between the upper and lower ends of said oscillating member and said frame.
25. A windmill operating mechanism comprising a frame, a motor driven shaft mounted therein, two pinions mounted on and spaced longitudinally of said shaft, two gear wheels meshing therewith and mounted in the frame, a reciprocating element between said gears provided with a cross-head, pitmen pivoted to crank pins on said gear wheels and to said cross-head, an oscillating member between said pitmen provided with side cheek plates, and with a recess to receive said reciprocating element and cross-head, said cheek plates being provided with apertures through which said cross head extends and in which it has bearing and pivotal connections between the upper and lower ends of said oscillating member and fixed parts of the frame.
30. A windmill operating mechanism comprising a frame, a motor driven shaft mounted therein, two pinions mounted on and spaced longitudinally of said shaft, two gear wheels meshing therewith and mounted in the frame, pitmen pivoted at their lower ends to crank pins on said gear wheels, a reciprocating element between said pitmen and pivotally connected at its upper end to the upper ends of said pitmen, and an oscillating member between said pitmen pivotally connected to the frame and to said reciprocating element.
35. A windmill operating mechanism comprising a frame, a motor driven shaft mounted therein, two pinions mounted on and spaced longitudinally of said shaft, two gear wheels meshing therewith and mounted in the frame, pitmen pivoted at their lower ends to crank pins on said gear wheels, a reciprocating element between said pitmen and pivotally connected at its upper end to the upper ends of said pitmen, and an oscillating member between said pitmen pivotally connected to the frame and to said reciprocating element.
40. A windmill operating mechanism comprising a frame, a motor driven shaft mounted therein, two pinions mounted on and spaced longitudinally of said shaft, two gear wheels meshing therewith and mounted in the frame, pitmen pivoted at their lower ends to crank pins on said gear wheels, a reciprocating element between said pitmen and pivotally connected at its upper end to the upper ends of said pitmen, and an oscillating member between said pitmen pivotally connected to the frame and to said reciprocating element.
45. A windmill operating mechanism comprising a frame, a motor driven shaft mounted therein, two pinions mounted on and spaced longitudinally of said shaft, two gear wheels meshing therewith and mounted in the frame, pitmen pivoted at their lower ends to crank pins on said gear wheels, a reciprocating element between said pitmen and pivotally connected at its upper end to the upper ends of said pitmen, and an oscillating member between said pitmen pivotally connected to the frame and to said reciprocating element.
50. A windmill operating mechanism comprising a frame, a motor driven shaft mounted therein, two pinions mounted on and spaced longitudinally of said shaft,

two gear wheels meshing therewith and mounted in the frame, pitmen pivoted at their lower ends to crank pins on said gear wheels, a reciprocating element between said pitmen and pivotally connected at its upper end to the upper ends of said pitmen, an oscillating member between said pitmen and pivotally connected between its ends to the reciprocating element, and links pivoted at their outer ends to fixed parts of the frame and pivoted at their inner ends respectively to the upper and lower ends of said member.

9. A windmill operating mechanism comprising a frame, a motor driven shaft mounted therein, two pinions mounted on and spaced longitudinally of said shaft, two gear wheels meshing therewith and mounted in the frame, a reciprocating element between said gears provided with a cross-head, pitmen pivoted to crank pins on said gear wheel and to said cross-head, an oscillating member between said pitmen and pivotally connected between its ends to said cross head and pivotal connections between the upper and lower ends of said oscillating member and said frame.

10. A windmill operating mechanism comprising a frame, a motor driven shaft mounted therein, two pinions mounted on and spaced longitudinally of said shaft, two gear wheels meshing therewith and mounted in the frame, a reciprocating element between said gears provided with a cross-head, pitmen pivoted to crank pins on said gear wheels and to said cross-head, an oscillating member between said pitmen provided with side cheek plates, and with a recess to receive said reciprocating element and cross-head, said cheek plates being provided with apertures through which said cross head extends and in which it has bearing and pivotal connections between the upper and lower ends of said oscillating member and fixed parts of the frame.

In testimony that we claim the foregoing as our invention we affix our signatures in the presence of two witnesses, this 20th day of April, A. D. 1914.
